ABSTRACT OF THE DISCLOSURE

Multiple latching functions for a longitudinally reciprocable member are produced by an arrangement of interrelated latches. An actuator bar interacts with the latches to provide a desired sequence of latching functions for the reciprocable member and the actuator bar.

BACKGROUND OF THE INVENTION**Field of the invention**

This invention relates generally to a latching mechanism, and more particularly this invention relates to an arrangement providing multiple latching functions for longitudinally reciprocable trays of a vending machine.

Description of the prior art

In many devices only a single cycle of operation of a longitudinally reciprocable member is desired upon actuation thereof, and a latching arrangement is employed at a position adjacent the bottom of the return stroke to engage the member and maintain it in its retracted position until subsequent actuation. A representative example of a device employing such an arrangement is a vending machine disclosed in a patent application entitled "Article Vending Apparatus" filed concurrently herewith in the names of A. G. Bodoh, O. J. Schwertfeger, and R. A. Johnson and assigned to the same assignee as this application. In such a device it is desired to have a reciprocable delivery mechanism dispense a single article when actuated by depositing a predetermined amount of money and selecting the particular type of article desired. Therefore, only a single reciprocating cycle of the delivery mechanism is desired in conjunction with a single actuation thereof, and a latching arrangement is employed to engage the mechanism following its return stroke to prevent multiple reciprocations and consequent multiple dispensing.

Furthermore, the latching functions may also involve other features of the overall vending apparatus. For example, an actuating mechanism for the latching arrangement may also be utilized to lockout other actuating mechanism to prevent the customer from making another selection. In such a case, it would be necessary to retain the actuating mechanism in the lockout position until the apparatus is prepared for another vending cycle to be initiated. Also, the actuating mechanism on the reciprocable member may be utilized for other lockout functions that would require a particular sequence of latch operation and positioning of the involved elements.

It is not possible to achieve the multiple functions described above with the conventional single latch biased to engage the delivery mechanism in its retracted position. Also, such an arrangement is particularly susceptible to the disadvantages of permitting unlimited dispensing if the bias fails and multiple dispensing if the latch is too slow in returning to its latching position.

Another approach would be to utilize an electrical control arrangement. This type of arrangement has the obvious disadvantages of being costly to construct and operate, of being much more cumbersome than mechanical

2

arrangements, and of being relatively unreliable. Furthermore, electrical switches could be opened or closed by the subjection of the vending device to physical force, resulting in vending without payment or multiple vending.

SUMMARY OF THE INVENTION

The latching mechanism of this invention is designed to obviate the difficulties noted above with respect to prior art arrangements. Briefly, in the preferred embodiment disclosed herein a stand-by latch lever and a safety latch lever are provided. Each of these levers has a hook-shaped head portion mounted on a mounting arm, and a leg portion attached to the end of the mounting arm away from the head portion and projecting at generally right angles from the mounting arm. The leg portions of the two levers extend generally in the same direction. The stand-by latch lever and the safety latch lever are commonly pivoted and are biased toward each other in a scissor fashion. A longitudinally reciprocable member, such as a stud or pin, is biased to an actuated position and is normally maintained in a normal latching position by the hook-shaped head portion of the stand-by latch lever. Reset means are provided to move the reciprocable stud, against its bias, from its actuated position to an overshoot position, removed from the normal latching in a direction opposite to the direction of bias of the reciprocable stud member, wherein it is latched by the safety latch lever.

30 A T-shaped actuator bar slidably mounted for longitudinal reciprocation, having a step intermediate its ends, is biased in a direction opposite to that of reciprocable stud. The cross piece of the T is at the end of the actuator bar adjacent the stand-by and safety latch levers, and the arm of the cross piece closest to the levers is provided with an actuator bar stud projecting outwardly from the actuator bar. The arm of the cross piece away from the levers is provided with a notched ear. Movement of the actuator bar against its bias is provided by a suitable actuating arrangement.

35 An inverted U-shaped actuator lever is pivotally mounted on a pivot through its bight, which pivot is at a point removed from the common pivot of the stand-by and safety latch levers. The leg of the U-shaped actuator bar farthest removed from the safety and stand-by latch levers is provided with a hook-shaped portion at its end, which is adapted to latch the actuator bar by engaging the notched ear thereof. The other leg of the U, adjacent the stand-by and latch levers, is provided with a depending arm projecting in the path of the reciprocable stud member at an angle with respect to the leg. The actuator bar lever is normally located in an unlatched position by engagement between the depending arm and the reciprocable stud member.

40 45 50 55 In utilizing the latching arrangement of this invention, the stud member is normally maintained in its normal latching position by the hook-shaped head of the stand-by latch lever, which is biased to its latching position. The reciprocable stud member is released to its actuated position by the actuating member's driving the actuator bar in a direction opposite to its bias, whereby the step on the actuator bar is caused to drivingly engage the leg of the stand-by latch lever and pivotally rotate the lever, against its bias, to its release position.

60 65 70 75 In its normal, biased position the actuator bar stud engages the projecting arm of the safety-latch lever and maintains it, against its bias, in a release position. Displacement of the actuator bar also causes the stud thereupon to disengage the projecting arm of the safety latch lever, whereupon the bias upon the safety latch lever causes it to pivotally rotate to its latching position in the path of the reciprocable stud member. The safety latch

lever does not latch the reciprocable stud member at this time, however, since the reciprocable stud member is not in its overshoot position.

Release of the stud member for movement to its actuated position also removes it from engagement with the projecting arm of the actuator latching lever, thus permitting that lever to move under the force of the bias applied thereto to be in position to engage the actuating bar.

Following full displacement of the actuator bar and upon deactivation of the actuating member, the actuator bar is caused by its bias to travel towards its normal biased position. After travelling a predetermined distance and before it reaches its normal, biased position, the actuator bar is latched by the engagement of the notched ear thereon by the hooked portion of the leg of the actuator bar lever. With the actuator bar in this position the stand-by latch lever is released to pivotally rotate to its latching position according to its bias.

Reset means are then actuated to cause the reciprocable stud member to travel in a direction opposite to its bias. The reciprocable stud member engages ramp faces on the stand-by latch lever and safety latch lever in this succession, causing them to pivotally rotate out of its path until it passes. The stud member is displaced past its normal latching position to an "overshoot" position, where it is latched by the safety-latch lever to prevent movement to its actuated position.

The actuator bar remains latched against movement towards its unactuated position by the hooked portion on the actuator latch lever during the reset stroke of the reciprocable stud member, until the stud member reaches its normal latched position. Thus, the actuator bar is maintained in its actuated position until the stud is relatched. Further, the stud is doubly latched, first by the safety latch lever and then by the stand-by latch lever, upon its return stroke to insure that the stud is latched upon the return stroke.

Upon reaching the normal latching position, the reciprocable stud member engages the depending arm of the actuator bar lever, causing the actuator bar lever to pivotally rotate against its bias to release the actuator bar. The actuator bar is thereby freed to travel to its normal rest or unactuated position. In the course of this travel the actuator bar stud engages the projecting arm of the safety latch lever causing it to pivotally rotate against its bias to release the reciprocable stud member from its "overshoot" position. The reciprocable stud member then moves to its normal latching position under its bias, where it is relatched by the stand-by latch lever.

Accordingly, a primary object of this invention is to provide a latching mechanism which prevents multiple reciprocations of a longitudinally reciprocable member.

Another object of this invention is to provide a latching mechanism in which an actuating arrangement is retained in an actuated position while a reciprocable member is unlatched.

Yet another object of this invention is to provide a latching mechanism in which a reciprocable member is temporarily latched in an "overshoot" position upon resetting thereof to an unactuated or rest position.

A further object of this invention is to provide a latching mechanism which prevents multiple reciprocations of a longitudinally reciprocating member which is particularly useful in connection with an article vending machine to prevent the multiple vending of articles without proper payment therefor.

These and other objects, advantages and features of the subject invention will hereinafter appear and, for purposes of illustration, but not of limitation, an exemplary embodiment of the subject invention is shown in the appended drawing.

BRIEF DESCRIPTION OF THE DRAWING

FIGURE 1 is a top plan view of a preferred embodiment of the latching mechanism of the present invention

in which a longitudinally reciprocating member is in its normally latched position.

FIGURE 2 is a top plan of the latching mechanism illustrated in FIGURE 1 and depicts the longitudinally reciprocable member released to its actuated position.

FIGURE 3 is a top plan view of the latching mechanism illustrated in FIGURE 1 and depicts the longitudinally reciprocable member still in its actuated position but with the latching mechanism in a configuration to prevent further reciprocation of the member.

FIGURE 4 is a top plan view of the latching mechanism illustrated in FIGURE 1 and depicts the longitudinally reciprocable member in the "overshoot" position.

DETAILED DESCRIPTION OF THE PREFERRED EMBODIMENT

The latching mechanism of this invention may be utilized in many environments, but for the purposes of this application it shall be described in the context of an Article Vending Machine claimed in an application filed concurrently herewith in the names of A. G. Bodoh, O. J. Schwertfeger, and R. A. Johnson, and assigned to the same assignee as the instant application. The Article Vending Machine application is directed toward an arrangement in which articles to be dispensed are located in a reciprocably movable tray which is displaced to a vend position for vending of a selected article. After the selected article has been dispensed the tray is reset. During the reset motion the tray is driven beyond its normal latched position to an overshoot position before returning to the normal latched position.

A lock-out mechanism is drivingly engaged by a sliding actuator to prevent vending more than one article at a time. To make the lock-out mechanism effective it is necessary to hold the sliding actuator engaged with the lock-out mechanism during the dispensing operation and until the tray is latched against further vending. Also it is desirable to provide protection against multiple vending due to the tray not being properly latched on the reset stroke. By using the present invention, these and other advantages may be obtained by utilizing a stud member 4 on the tray to interact with the latching mechanism of the present invention.

Referring to FIGURES 1-4, a stand-by latch lever 6 has a triangularly shaped head 8, a mounting arm 10, and a depending leg 12, with arm 10 and leg 12 extending from a circular pivot mounting 13 on a pivot 22 at essentially ninety degrees from each other. Triangularly shaped head 8, has a generally right-triangle configuration, the sides being of unequal length, with the hypotenuse of the triangular perimeter providing a ramp 9 (FIGURE 2) for cammingly engaging stud member 4. Mounting arm 10 is attached to the short side of the head, adjacent the right angle and away from the vertex formed by the hypotenuse and the short side and has a width at the head approximately one-half the length of the short side of the triangle, so that the remainder of the short side of the triangle forms a hook face 11 (FIGURE 2) adapted to engage and latch stud member 4. Circular pivot mounting 13 is attached to mounting arm 10 at its end away from the head and leg 12 is attached to the pivot mounting in a manner such that it forms a generally right angle with respect to mounting arm 10.

Stand-by latch lever 6 is biased for pivotal rotation in a counter-clockwise direction by tension spring 24, one end of which is firmly attached to mounting arm 10 at a point 25 intermediate its ends. Stand-by latch lever 6 normally assumes its biased position, in which hook face 11 is in the path of stud member 4 to engage and latch it in its normally latched position (FIGURE 1) and thereby prevent movement of stud 4 to an actuated position (FIGURE 2). Stud member 4 is normally biased toward its actuated position (indicated schematically in FIGURES 1-4 by tension spring 2). When stand-by latch lever 6 is caused to pivotally rotate about pivot 22 in a clock-

wise direction to the FIGURE 2 position against the force of bias spring 24, causing triangle-shaped head 8 and mounting arm 10 to similarly pivotally rotate in a clockwise direction, stud member 4 is released to move to its actuated position under the force of spring 2. When latch lever 6 is released, the bias of spring 24 causes lever 6 to rotate to the normal latching position. Return of stud 4 toward its normally latched position brings it into engagement with ramp 9 of latch lever 6 to cause latch lever 6 to pivotally rotate against the bias of spring 24, in a clockwise direction, whereby the head 8 is temporarily driven out of the path of stud member 4, by the stud member 4, permitting the stud member to continue its travel to an "overshoot" position (FIGURE 4). After stud 4 passes the head 8 on its way to its overshoot position, the biasing force of spring 24 immediately returns stand-by latch lever 6 to its normal latching position. This configuration is illustrated in FIGURE 4.

A safety latch lever 14 is illustrated (FIGURES 1-4) as having a triangularly shaped head 16, a mounting arm 18, a circular pivot mounting 19, and a depending leg 20. Triangularly shaped head 16 has a generally right triangle configuration whose sides are of unequal length with the hypotenuse providing a ramp 15 for cammingly engaging stud member 4. Mounting arm 18 is attached to the short side of the triangularly shaped head, adjacent the right angle and away from the vertex formed by the hypotenuse and the short side, and has a width approximately one-half the length of the short side of the triangle so that the remainder of the short side forms a hook face 17 adapted to engage stud member 4. Circular pivot mounting 19 is attached to mounting arm 18 at its end away from head 16, and leg 20 is attached to mounting arm 18 at a generally right angle with respect thereto. Leg 20 extends in generally the same direction as leg 12 of stand-by latch lever 6. Safety latch lever 14 is pivotally mounted on pivot 22, in common with stand-by latch lever 6 in a "scissors" fashion. Lever 14 is biased for pivotal rotation in a clockwise direction by tension spring 24, one end of which is firmly attached intermediate the ends of mounting arm 18 at a point 21. The other end of spring 24 is firmly attached to mounting arm 10 of stand-by latch lever 6, as previously described.

Safety latch lever 14 is normally held in a release position while stud member 4 is latched in its normally latched position by stand-by latch lever 6. After stud 4 is unlatched by stand-by latch lever 6, safety latch lever 14 is freed to rotate into a position to latch stud 4 by spring 24. Of course, stud 4 is not in position to be latched, but as stud 4 is returned beyond the latched position it engages ramp 15 of lever 14 and causes it to rotate out of the way until stud 4 can pass. Immediately after stud 4 passes the end of latch 14, spring 24 returns latch 14 to the latch position so that stud member 4 will be latched in the "overshoot" position. Lever 14 is subsequently rotated counter-clockwise to release stud 4 so that it will move to engage latch lever 6 and be latched in the latch position.

A pivoted generally U-shaped actuator latch lever 32 has a bight 34 and two legs, 38 and 40, respectively. A triangularly shaped foot 42 has a generally right-triangle configuration with the hypotenuse providing a ramp 39. Foot 42 is attached to the end of leg 38 away from the bight along a side of the triangle adjacent the right angle. The width of leg 38 is less than that of the side of the triangle to which it is attached, so that the remainder of the side forms of hook face 43. Leg 40 is attached to the end of bight 34 away from leg 38 and extends generally in the direction of stud member 4 in its overshoot position. A depending foot 44, having generally the configuration of a trapezoid, is integrally formed with the end of leg 40 away from bight 34. A notch face 45 of foot 44 is adapted to engage stud 4, and end 47 of foot 44 is formed with an angular slope to act as a cam to pivot lever 32 when stud 4 is engaged therewith. Actuator latch

lever 32 is pivotally mounted for pivotal rotation about pivot 46, which passes through pivot mounting 48 attached to the bight 34 of actuator latch lever 32. Actuator latch lever 32 is normally biased in a counter-clockwise direction by a spring 50.

An actuator bar 30 is slidably mounted for longitudinal reciprocation on mounting member 50. Actuator bar 30 is biased toward its normal unactuated position by a bias member (shown schematically as a tension spring 68 in FIGURES 1-4).

Actuator bar 30 has a body portion 52 and a T-shaped head portion 53 attached to the end of body portion 52 adjacent latch levers 6, 14 and 32. A base 54 of the T-shaped head portion 53 is of smaller width than the body portion 52 and offset therefrom in a direction away from the latch levers 6 and 14 so that the remainder of the end of the body 52 forms a step 56. Step 56 is adapted to drivingly engage leg 12 of stand-by latch lever 6 when the actuator bar is actuated, to cause stand-by latch lever 6 to pivotally rotate in a clockwise direction, whereby hook 11 is rotated out of engagement with stud member 4 to release stud 4 for movement to its biased vend actuated position.

A crosspiece 58 of the T-shaped head portion 53 is attached to the end of base 54 adjacent the latch levers. A depending arm 60 of the crosspiece away from the levers has a rounded top arm portion 62 adapted to cammingly engage ramp 39 of actuator latch lever 32 when actuator latch lever 30 is actuated, whereby foot 42 is pivotally rotated out of the path of actuator bar 30 on its actuating stroke. The bottom of the depending arm 60 makes generally a right angle with base 54 so that a latching face 64 is formed. Latching face 64 is adapted to engage hook 43 of actuator latch lever 32 when stud member 4 is unlatched (FIGURES 3 and 4).

An upwardly projecting actuator bar stud 66 is attached to the right hand arm 61 of the crosspiece 58 of the T-shaped head portion. The stud 66 is adapted to drivingly engage leg 20 of safety latch lever 14 whereby safety latch lever 14 is caused to pivotally rotate in a counter-clockwise direction which rotates hook 17 out of engagement with stud 4 and frees stud 4 to travel to its normally latched position (FIGURE 1).

Prior to actuation of actuator bar 30, actuator latch lever 32 is disengaged from actuator bar 30, and stud 4 engages notch face 45 on foot 44 of actuator latch lever 32, whereby the actuator latch is normally maintained in a position wherein hook face 43 is not positioned to latch actuator bar 30. In this unlatched state, stud 66 on actuator bar 30 engages leg 20 of safety latch lever 14 and holds lever 14 in the unlatched position. Bias spring 24 holds stand-by latch 6 in the latch position.

Upon actuation stud 66 is removed from engagement with leg 20 of lever 14, but the end of hook surface 17 bears against stud 4 and is prevented from moving. Further displacement of the actuator bar 30 caused rounded top arm portion 62 to cammingly engage ramp 39 on foot 42 to pivotally rotate actuator latch lever 32 against its bias, in a clockwise direction, and foot 42 is temporarily driven out of the path of actuator bar 30, permitting the actuator bar 30 to be driven by the actuating force to its actuated position (shown in FIGURE 2). Still further displacement of actuator bar 30 results in step 56 on bar 30 engaging leg 12 of latch 6 to drive the latter to unlatch the stud member 4 for movement to its actuated position, whereby stud member 4 disengages notch face 45 of actuator latch lever 34 and the biasing force on the actuator latch lever causes it to pivotally rotate in a counter-clockwise direction moving the foot 42 into the path of the actuator member. Upon deactuation of actuator bar 30, it is driven towards its normal biased or rest position by a biasing force acting thereupon. After a partial displacement in this direction, actuator bar 30 is intercepted and latched against further displacement by hook 43 of actuator latch lever 34 which engages latching

surface 64. This partial displacement is sufficient to permit leg 12 of stand-by latch lever 6, although it is still engaged by the actuator bar, to pivotally rotate, according to its bias, in a counter-clockwise direction whereby hook 11 of stand-by latch lever 6 is rotated into the path of stud member 4 (FIGURE 3).

A reset arrangement (not shown) is then actuated to drive the stud member 4 against its bias from its actuated position to its overshoot position. As hereinbefore described, the stud 4 cammingly engages stand-by latch lever 6 and safety latch lever 14 on this return stroke and each is immediately returned to its latching position after disengagement by the stud, to prevent movement of the stud to its actuated position. Actuator bar 30 remains latched against movement towards its biased, unactuated position by hook face 43 of actuator latch lever 32 during the return stroke of stud 4 until the stud member reaches its "overshoot" position, wherein it is latched by hook face 17 of safety latch lever 14. Thus, until the stud 4 reaches its overshoot position, the actuator bar 20 is restrained from re-engaging leg 20 of safety latch lever 14 to cause it to pivotally rotate to its release position. Since stud 4 is latched, in its overshoot position, against movement toward its actuated position by safety latch 14, and actuator bar 30 is latched against return to its rest 25 position by actuator latch lever 32 multiple reciprocations of stud 4 cannot occur. When stud 4 is driven to its overshoot position, it drivingly engages notch face 45 of actuator latch lever 32 and causes the actuator latch lever to pivotally rotate, against its bias, in a clockwise direction, whereby the hook face 43 of actuator latch lever 32 is rotated out of engagement with actuator bar 30 and the actuator bar is released to travel to its normal biased or rest position. This configuration is illustrated in 30 FIGURE 4. On its return stroke, actuator bar 30 drivingly engages leg 20 of safety latch lever 14 and causes it to pivotally rotate, against its bias, in a counter-clockwise direction, whereby hook 17 of safety latch lever 14 is rotated out of engagement with stud member 4 and the stud member is freed to move to its normal latching position wherein it is latched by hook 11 of stand-by latch lever 6. Thereupon, the configuration illustrated in FIGURE 1 is again assumed and the arrangement is in a 35 position to perform another cycle of operation.

It should be recognized that the embodiments described herein are merely exemplary of the present invention and that various changes, modifications, and variations may be made in the arrangements, operations, and details of construction of the elements disclosed herein, without departing from the spirit and scope of the present invention.

What I claim is:

1. A latching arrangement for a reciprocable member biased to an actuated position and returned from the actuated position by a suitable driving arrangement comprising:

a first latch means adapted to normally latch the reciprocable member in a first retracted position; a second latch means adapted to latch the reciprocable member in a second retracted position; and an actuator member adapted, upon energization thereof, to cause said first latch means to release the reciprocable member for movement to the actuated position, and whereby return of the reciprocable member to the second retracted position causes the reciprocable member to be temporarily latched in said second retracted position by said second latch means prior to relatching of the reciprocable member in said first retracted position by said first latch means.

2. A latching arrangement as claimed in claim 1 and further comprising a third latch means biased to engagement with said actuator member but normally disengaged therefrom, said third latch means being adapted to latch said actuator member following the release of

the reciprocable member by said first latch means and to release said actuator member upon the return of the reciprocable member to said second retracted position.

3. A latching arrangement as claimed in claim 2 wherein:

5 said first latch means comprises a first pivoted lever having a latching surface and an extending leg; said second latch means comprises a second pivoted lever having a latching surface and an extending leg, said latching surfaces on said first and second levers being adapted to engage the reciprocable member; said third latch means comprises a third pivoted lever having a latching surface and an extending leg; said actuator member has a notched ear thereon adapted to be engaged by said latching surface on said third lever to latch said actuator member in its actuated position; said extending leg of said third lever has a projection thereon adapted to engage the reciprocable member to be actuated thereby to rotate said third lever and prevent engagement of said latching surface thereon with said notched ear on said actuator member; said actuator member has a step formed thereon adapted to engage said extending leg on said first lever to rotate said first lever and prevent the latching surface thereon from engaging the reciprocable member; and said actuator member has a stud connected thereto adapted to engage said second lever to rotate said first lever and prevent the latching surface thereon from engaging the reciprocable member.

4. A latching arrangement as claimed in claim 2 wherein:

35 in said third latch means comprises:
a first leg having a triangularly-shaped head portion and a mounting arm extending from one side of said portion, said arm having a width substantially less than the length of said side of said head portion so that the remainder of said side forms a hook surface;
a bight portion attached to the end of said first leg away from said head portion;
a pivot mounting extending through said bight portion, at a point intermediate its ends;
a second leg attached to the end of said bight portion away from said first leg; and
a projecting arm attached to the end of said second leg away from said bight portion.

5. A latching arrangement as claimed in claims 1 or 2 wherein said first and second latch means comprise hooked levers pivoted about a common pivot point and biased toward each other in a scissors fashion, adapted to permit engagement and disengagement thereof by said actuator member.

6. A latching arrangement as claimed in claims 1 or 2 wherein said first and second latch means comprise 60 hooked levers pivoted about a common pivot point and biased toward each other in a scissors fashion, and each of said hooked levers comprises:

a triangularly shaped head portion;
a mounting arm extending from one side of said head portion, said arm having a width substantially less than the length of said side of said head portion so that the remainder of said side forms a hooking surface;
a pivot mounting extending through the end of said mounting arm away from said head portion; and
a depending leg portion projecting at an angle with respect to said mounting arm and adapted to engage said actuator member.

7. A latching arrangement as claimed in claims 1 or 2

wherein said actuator member is mounted for longitudinally reciprocable movement and comprises:

- a T-shaped head portion, one arm of the crosspiece of said T-shaped head portion forming a notched ear adapted to be engaged by said third latch means;
- a stud mounted on the arm of the crosspiece of said T-shaped head portion away from said notched ear and extending outwardly from said actuator member, said stud adapted to engage said second latch means to cause said second latch means to release the reciprocable member from its second retracted position; and
- a mounting arm extending from the end of the leg of said T-shaped head portion and having a width sub-

stantially greater than that of said leg so that a step is formed at the junction of said mounting arm and said base, said step being adapted to engage said first latch means to cause said first latch means to release the reciprocable member from its first retracted position.
